CONTROL DEVICE FOR DOUGHNUT MACHINES

Filed May 21, 1938

UNITED STATES PATENT OFFICE

2,231,667

CONTROL DEVICE FOR DOUGHNUT MACHINES

Verne V. Gunsolley, Minneapolis, Minn., assignor to Dough-King, Inc., Minneapolis, Minn., a corporation of Minnesota

Application May 21, 1938, Serial No. 209,262

9 Claims. (Cl. 53—7)

My invention relates to control devices for doughnut machines and particularly to a device for controlling the travel of doughnuts to a doughnut turner or ejector of the continuous type such as disclosed in the application for patent to Peter J. Toews, Serial Number 114,395 filed Dec. 5, 1936.

An object of the invention resides in providing a device by means of which the travel of doughnuts is positively and effectively controlled.

Another object of the invention resides in providing a device which will not injure the doughnuts.

A still further object of the invention resides in providing a device which assists in causing the doughnuts to travel along their desired course when the doughnut is released.

Another object of the invention resides in providing a control device in which a member engages the doughnut from beneath.

A still further object of the invention resides in providing a control device having an engaging member in which the engaging member engages the doughnut to be released in a manner such that the doughnut is raised at the tail end of the same so as to cause the doughnut to move by gravity off from the engaging member and caused to be discharged ahead of the same.

Another object of the invention resides in providing a control device having two engaging members and in arranging one of said engaging members for movement from beneath the doughnut and the other one for movement from above the doughnut.

A feature of the invention resides in providing means for simultaneously operating both the said engaging members.

Another object of the invention resides in providing a control device in which the space between the submerged engaging member and the bottom of the trough in which the device is disposed is at all times closed.

A still further object of the invention resides in constructing the submerged engaging member with two parts hingedly connected together at corresponding ends and adapted to slide along the bottom of the trough of the doughnut machine at their other ends.

Other objects of the invention reside in the novel combination and arrangement of parts and in the details of construction hereinafter illustrated and/or described.

In the drawing:

Fig. 1 is a plan view of a portion of a doughnut

machine illustrating an embodiment of my invention applied thereto.

Fig. 2 is a vertical sectional view of the structure shown in Fig. 1 and taken on line 2—2 of Fig. 1.

Fig. 3 is a view similar to Fig. 2 showing the parts in altered position.

In the application for patent of Peter J. Toews, above referred to, a doughnut machine is disclosed in which the doughnuts are deposited in a cooking liquid contained in a pan or receptacle providing a way along which the doughnuts may travel and in which the doughnuts are progressed through propulsion of cooking liquid. In this way are disposed a turner and an ejector both of the continuous type which are adapted to turn or eject the doughnuts any time the doughnuts reach the same. With such devices it becomes necessary to provide some means for controlling the rate of travel of the doughnuts to the turner or ejector which, in the application of patent shown, consisted of a pair of alternately movable gates. The present invention is of the nature of the said gates and may be used in substitution thereof.

Inasmuch as the construction of doughnut machines with which my invention may be used is well known in the art, a complete doughnut machine has not been illustrated in this application and only so much of the doughnut machine as is necessary to describe the present invention has been shown.

In the drawing a portion of a doughnut machine A has been illustrated which consists of a pan 10 having a way 11 in the same. This pan contains the cooking liquid the level of which is indicated by the reference numeral 12. The cooking liquid travels as previously described in the direction of the arrow as shown in Fig. 2 and causes the progression of doughnuts along the way, the doughnuts floating along the surface of the cooking liquid. The pan 10 is constructed with side walls 13 and 14 and a bottom 15 connected therewith.

The invention proper comprises two engaging members which are indicated in their entireties by the reference numerals 16 and 17. These engaging members are supported and operated as will now be described in detail.

The engaging member 16 consists of a shaft, or cylindrical rod 18, which is attached at its ends to a U-shaped frame 19. Frame 19 consists of two legs or slides 21 which are connected together at their upper ends through a cross bar 22. This frame may be constructed from a strip

of metal bent into the desired form, if desired. The two slides 21 are slidably mounted for reciprocating movement in two U-shaped guides 23, secured to the sides 13 and 14 of the pan 10. These guides are constructed with a back 24 and outwardly turned edges 25 which form in said guides grooves 26 in which the slides 21 may slide. The guides 23 are preferably recessed into the walls 13 and 14 of the pan 10 so that the edges of said guides do not protrude beyond the inner surfaces of said walls whereby the possibility of the doughnuts catching on said walls is prevented. The guides 23 are preferably arranged on an angle as shown in Figs. 2 and 3, the purpose of which will be subsequently explained.

Pivoted on the rod 18 are a number of fingers 27. These fingers are constructed of wire and have bent, at the upper ends thereof, loops 28 which extend about the shaft or rod 18 and which serve to pivot said fingers on said rod. The other ends of said fingers are provided with similar loops 29 which ride upon the bottom 15 of the pan 10. These loops merely form bearing surfaces to prevent the rods from catching on the bottom as the device is manipulated. The fingers 27 extend rearwardly of the rod 18. The various fingers 27 are bent, as designated at 54 so that, when the frame 19 is in its uppermost position, portions 55 of the said fingers extend vertically adjacent the loops 28 of the engaging member 16 and prevent the doughnuts from climbing over said portions. The engaging member 16 also comprises other fingers 31, similar to the fingers 27, which extend forwardly of the rod 18. These fingers are likewise constructed with loops 32 which are pivoted on the rod 18 and with loops 33 which slide along the bottom 15 of pan 10. Between the various loops 28 and 32 are arranged spacer washers 34 which hold the fingers in spaced relation and prevent lateral movement of the said fingers. The portion of the engaging member 16 which engages the underside of the doughnut consists of the various loops 28 and 32 of the fingers 27 and 31 and will be referred to by the reference numeral 56.

The upper end of the cross bar 22, of the frame 19, has secured to it a yoke 35. This yoke is constructed with a slot 36 which forms two arms 37 extending outwardly in spaced relation. Pivoted by means of a pin 40 to the yoke 35 between the arms 37 is a link 43. A lever 38 is mounted on a shaft 39 which is journaled in bearings 41, secured to the walls 13 and 14 of the pan 10. This lever has a head 42 which is bifurcated similarly to the yoke 35. A pin 44 passes through the link 43 and the head 42 and forms a pivotal connection therebetween. It will be readily comprehended that, upon oscillation of the shaft 39, the lever 38 is swung and the frame 19 slid along the guides 23. For operating the shaft 39 a crank arm 45 is employed which has connected to it a link 46 which may be driven by any suitable means forming a part of the transmission of the doughnut machine.

The engaging member 17 consists of a plate of metal bent to provide an arm 47 and a finger 48 issuing therefrom. Arm 47 underlies the cross bar 22 of frame 19 and is secured thereto by means of rivets 49. The engaging member 17 is so constructed that the finger 48 lies parallel with the slides 21.

The operation of the invention is as follows: Normally the parts have the position as shown in Fig. 2 and the doughnuts indicated by the ref-

erence numerals 57 and 58 lie back of the engaging member 16, the doughnut 58 engaging the portions 55 of the fingers 27. When the frame 19 is moved to its lowermost position, as shown in Fig. 3, the engaging member 16 is situated entirely below the doughnuts floating in the cooking liquid in the pan 10. As soon as the engaging portion 56, of the engaging member 16, passes below the doughnut 58 all of the doughnuts in the row travel in the direction of the arrow. As soon as the engaging portion 56 passes below the doughnut, the edge 53 of finger 48 is moved into the path of travel of the doughnuts and the doughnuts become arrested in the position shown in Fig. 3 in which the doughnut 58 is now held back by the said finger. When the frame 19 is again elevated the engaging portion 56 engages the doughnut 58 from beneath and tilts the same upwardly, as indicated in dotted lines at 58a in Fig. 2. It will be noted that the device is so shaped that the portion 56 engages the doughnut rearwardly of the center of gravity of the same so that the doughnut is tilted forwardly. The doughnut then slides off of engaging portion 56 and along the fingers 31, being discharged beneath the edge 53 of finger 48 and into the cooking liquid beyond the control device. As the doughnut 58 is discharged the next following doughnut is brought up into engagement with the portions 55 of fingers 27 whereupon the movement of the doughnuts is again arrested. The device then operates repeatedly through the same cycle, thus controlling the travel of the doughnuts along the way 41. It will be noted that the lowermost portion of the finger 48, which determines when the doughnuts are freed thereby, is situated a distance above the loops 28 and 32 of the fingers 27 and 31 somewhat greater than the thickness of the doughnut so that a doughnut when disposed, as indicated at dotted lines at 58a in Fig. 2, may pass over the said loops and beneath the edge 53 of said finger.

The advantages of my invention are manifest. An extremely simple and practical construction is provided whereby the travel of the doughnuts through the doughnut machine is positively controlled. By arranging one of the engaging members to engage the doughnut from beneath and the other to engage it from above, a rigid combined structure results which will not get out of adjustment. By so constructing the device both parts are simultaneously operated and a single operating member may be used to actuate the movement of both of said parts. By arranging the guides for the frame on an incline, the doughnut, on being released, is urged in the direction of travel of the cooking liquid and impetus is given the doughnut to commence to travel in the proper direction. By engaging the doughnut from underneath at the locality specified, the doughnut is caused to slide off of the engaging member and in the proper direction. In this manner it becomes impossible to block the action of the device and the doughnuts are positively disengaged from the same. With my invention an extremely great range of fat elevation is possible, the device operating at any fat elevation within wide limits. By use of the two sets of fingers pivoted together and slidable along the bottom of the trough, the space beneath the engaging portion of the engaging member is at all times closed so that it becomes impossible for doughnuts to become lodged beneath the engaging member or between it and the bottom of the trough. The device is thus rendered positive in

action. By arranging the guides on an incline as illustrated, movement of the engaging members is partly in the direction of travel of the cooking liquid so that the devices does not back up the doughnuts and injury to the doughnuts is prevented.

Changes in the specific form of my invention, as herein disclosed, may be made within the scope of what is claimed without departing from the spirit of my invention.

Having described my invention, what I claim as new and desire to protect by Letters Patent is:

1. In a doughnut machine in which the doughnuts are progressed along a way through the flow of the cooking liquid, a movable support movable transversely of the direction of the flow of the cooking liquid, an engaging member carried by said support and adapted to be moved into engagement with the doughnuts from one side thereof, a second engaging member carried by said support and disposed in fixed relation with respect to the first named engaging member and adapted to engage the doughnut from the opposite side thereof, means for guiding said support for movement obliquely with respect to the direction of travel of the cooking liquid and means for moving said support to procure alternate engagement of said engaging members with the doughnut.

2. In a doughnut machine in which the doughnuts are progressed along a way through the flow of the cooking liquid, an engaging member adapted to be moved into engagement with the doughnuts from beneath, said engaging member comprising two ramps pivoted together at their upper ends and slideable at their lower ends along the bottom of said way, said ramps being adapted in one position of the engaging member to lie substantially in continuation of one another to allow the doughnuts to travel above the same and in another position to be arranged in the form of an inverted V to obstruct the travel of doughnuts past the same.

3. In a doughnut machine in which the doughnuts are progressed in a row along a way through the flow of the cooking liquid and engaging member, means for guiding said engaging member for movement from a non-engaging position to a position engaging the last doughnut in the row, a second engaging member, means for guiding said second engaging member for movement from a position beneath the doughnuts to a position engaging the same doughnut intermediate the center thereof and the next doughnut, said second engaging member during its movement engaging the doughnut from beneath and raising the rear end of the doughnut to cause the same to slide off from said engaging member as the same is raised and means for moving the first named engaging member out of engagement with the doughnut to allow the doughnut to be discharged from the second named engaging member.

4. In a doughnut machine in which the doughnuts are progressed along a way through the flow of the cooking liquid, a U-shaped frame having two legs and a connecting portion, a rod extending across said legs at the free ends thereof, two ramps pivoted on said rod and adapted to swing upon movement of said frame and a finger carried by said frame, said ramps and finger being movable to control the travel of the doughnut past the same.

5. In a doughnut machine having a channel formed with side walls and a bottom in which

the doughnuts are progressed through the flow of the cooking liquid, an engaging member adapted to be moved into engagement with the doughnuts from beneath, said member being disposed between the side walls of the channel, said engaging member comprising two ramps pivoted together at their upper ends and extending downwardly toward the bottom, means for raising the upper ends of said ramps to move the engaging member from inoperative to engaging position, the lower ends of said ramps during movement of the upper ends thereof following along the bottom and maintaining the space between the upper ends of the ramps and the bottom obstructed to prevent the entry of doughnuts beneath the engaging member.

6. In a doughnut machine having a channel formed with side walls and a bottom in which the doughnuts are progressed through the flow of the cooking liquid, an engaging member adapted to be moved into engagement with the doughnuts from beneath, said member being disposed between the side walls of the channel, said engaging member comprising two ramps pivoted together at their upper ends and extending downwardly toward the bottom, means for raising the upper ends of said ramps to move the engaging member from inoperative to engaging position, the lower ends of said ramps during movement of the upper ends thereof sliding along the bottom of the way and maintaining the space between the upper ends of the ramps and the bottom obstructed to prevent the entry of doughnuts between the engaging member and the bottom, said ramps, when in raised position, forming an inverted V to obstruct the doughnuts past the same.

7. In a doughnut machine having a channel formed with side walls and a bottom in which the doughnuts are progressed through the flow of the cooking liquid, an engaging member adapted to be moved into engagement with the doughnuts from beneath, said member being disposed between the side walls of the channel, said engaging member comprising two ramps pivoted together at their upper ends, means for guiding the upper ends of the ramp for up-and-down movement and means for guiding the lower ends of the ramps for longitudinal movement with respect to the direction of flow of the cooking liquid in the channel.

8. In a doughnut machine in which the doughnuts are progressed in a row along a way through the flow of the cooking liquid, an engaging member for engaging the last doughnut in the row, a second engaging member spaced from the first engaging member a distance less than the maximum diameter of a doughnut and adapted to engage the last doughnut in the row intermediate the ends thereof and from beneath, means for moving said engaging members in alternation to bring the first engaging member out of engagement with the last doughnut in the row and the second engaging member into engagement with the same doughnut, said second named engaging member when in engaging position obstructing the movement of the following doughnut in the row.

9. In a doughnut machine in which the doughnuts are progressed in a row along a way through the flow of the cooking liquid, an engaging member for engaging the last doughnut in the row, a second engaging member spaced from the first engaging member a distance less than the maximum diameter of a doughnut and adapted to

engage the last doughnut in the row intermediate the ends thereof and from beneath, means for moving said engaging members in alternation to bring the first engaging member out of engagement with the last doughnut in the row and the second engaging member into engagement with the same doughnut, and a skid

formed on said second named engaging member for causing the doughnut engaged thereby to slide off from the same, said second named engaging member when in engaging position obstructing the movement of the following doughnut in the row.

VERNE V. GUNSOLEY.
